(57) **CLAIM**

The ornamental design for an animal excluder device, as shown and described.

DESCRIPTION

FIG. 1 is a perspective view of an animal excluder device with the door shown in a closed position;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, shown with the door in an open position; and,

FIG. 9 is a section view along line 9-9 in FIG. 2.

The broken lines illustrate portions of the animal excluder device that form no part of the claimed design.

1 Claim, 9 Drawing Sheets
